UNITED STATES PATENT OFFICE.

PHILIP K. MUSSelman, OF DUBLIN, PENNSYLVANIA.

CABLE-SUPPORT.

1,084,225.

Specification of Letters Patent. Patented Jan. 13, 1914.

Original application filed March 11, 1913, Serial No. 753,487. Divided and this application filed May 27, 1913. Serial No. 770,138.

To all whom it may concern:

Be it known that I, PHILIP K. MUSSelman, a citizen of the United States, residing at Dublin, in the county of Bucks and State 5 of Pennsylvania, have invented certain new and useful Improvements in Cable-Supports, of which the following is a specification.

My invention relates to improvements in cable supports, the object of the invention 10 being to provide an improved attachment for a barn or like building which will so support the cable for a carrier that the cable may be raised and lowered whenever desired.

A further object is to provide an improved cable support of this character which enables the cable to be elevated out of the way of the door when not in use.

20 This is a division of my application for patent on improvements in carriers, filed March 11, 1913, and given Serial No. 753,487.

With these and other objects in view, the 25 invention consists in certain novel features of construction and combinations and arrangements of parts as will be more fully hereinafter described and pointed out in the claims.

30 In the accompanying drawings: Figure 1 is a view illustrating my improvements in connection with a barn. Fig. 2 is a plan view on an enlarged scale of my improved cable supporting device, and Fig. 3 is a view 35 in elevation showing the supporting device in position on a barn and its supporting means.

1 represents an ordinary barn through the door 2 of which, a carrier 3 is adapted to run. This carrier is provided with wheels 40 which run upon a cable 5. This cable 5 is connected at its outer end with a vertically movable supporting device 6, so that the cable may be elevated or lowered at this outer end and compel the carrier to 45 run by gravity in both directions.

My improved support 45 is located at the barn and holds the cable in the arc of a circle, so that the car may follow the cable 50 in a direction at an angle to the barn without danger of the wheels leaving the cable. The support 45 comprises a frame consisting of a plurality of radially positioned bars 46 connected by transverse bars 47. The

central bar of the frame is longer than the 55 others, and is connected by a suitable hinge connection 48 with the barn, so that the device may be raised and lowered. The outer ends of all of the bars 46 are provided with cable clamps 49, so that the cable 5 is held 60 therein, yet the wheels 4 are permitted to pass over the clamps, because the latter are of thin sheet metal and would not derail the device. This support, when in normal position, lies in front of the door as indicated 65 in Figs. 1 and 3. To support it in this position and elevate the same out of the way when not in use, I provide an adjustable hanger as shown most clearly in Fig. 3. This hanger comprises two bars 50 and 51 70 which are connected by straps 52, so that they slide one beside the other. A cam lever 53 is connected to bar 51, and is connected by links 54 with the bar 50. The upper end of bar 51 is secured to a fixed support 55, 75 so that when the lever 53 is raised and lowered, the support 45 will be raised and lowered. When raised, it will hold the cable 80 out of the doorway, so that the door may be shut.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by 90 Letters Patent is:

1. The combination with a cable, a frame pivotally supported at one end, and at its other end comprising a curved mounting for a cable, and a longitudinally adjustable support comprising two members movable relative to each other, the upper member secured to a fixed part, and the lower member connected to said cable support, substantially as described.

2. The combination with a building having a door therein, of a frame pivotally connected at one end to the building and at its free end forming a curved cable support normally positioned in front of the door, a 105 hanger connected at its upper end to the building and at its lower end to the cable support, said hanger comprising two bars

having sliding relation side by side, a cam lever on one bar, links connecting the cam lever with the other of said bars, a cable secured in the cable support, and a carrier mounted to run on said cable, substantially as described.

In testimony whereof I have signed my

name to this specification in the presence of two subscribing witnesses.

PHILIP K. MUSSELMAN.
